UNITED STATES PATENT OFFICE.

EDWARD C. LYITTLE, OF WATERTOWN, NEW YORK.

GLARE-REFLECTOR.

1,399,356.

Specification of Letters Patent. Patented Dec. 6, 1921.

Application filed February 24, 1921. Serial No. 447,399.

To all whom it may concern:

Be it known that I, EDWARD C. LYITTLE, a citizen of the United States, residing at Watertown, in the county of Jefferson and State of New York, have invented certain new and useful Improvements in Glare-Reflectors, of which the following is a specification.

This invention relates to certain new and 10 useful improvements in devices adapted to attach to auto vehicles, for preventing the driver thereof from being affected by the blinding headlights of other approaching vehicles.

15 Primarily, my invention has for its purpose to provide means of the general character stated, relatively inexpensive to manufacture, that can be readily applied to any of the conventional wind shield supporting frames, in position for protecting the eyes of the vehicle driver, without materially cutting off vision, and by which the intense light rays from an approaching vehicle may be reflected in such manner, whereby some 20 of the light of the said approaching vehicle is turned to one side of the road, ahead of the vehicle equipped with my invention.

Another object of my invention is to provide a glare reflector adapted to different 30 adjustments for reflecting back the glare of an approaching light along the road ahead and it has provision for permitting the driver looking, with one eye, directly through the reflecting device while his other eye is free 35 to look over the outer edge of the said device for a clear observation of conditions ahead.

With other minor objects in view that will be hereinafter apparent, my invention is a 40 glare reflecting means which embodies the peculiar features of construction and peculiar combination of parts, all of which will be fully explained in the following detailed description, specifically pointed out in the 45 appended claims and illustrated in the accompanying drawing, in which:

Figure 1 is a perspective view of my invention, so much of an auto vehicle being shown necessary to illustrate a practical application of my said invention.

Fig. 2 is an elevation of my improved device, viewed from the inside of the vehicle and in its operative position.

Fig. 3 is a top plan view thereof, the reflector supporting frame being indicated to different angled adjustments.

Fig. 4 is a transverse vertical section thereof, the reflector frame being shown at different vertical adjustments, in dotted lines.

Fig. 5 is a detail perspective view of the reflector mirror, part of its metal frame being shown in section.

Fig. 6 is a detailed perspective view of parts hereinafter particularly referred to.

In the practical development of my invention, I provide a mounting rod 1 with its ends suitably shaped for being secured or bolted on one of the side standards of the wind shield supporting frame, the said rod 70 1 forming the supporting member for the glare reflector devices, the special construction of which is clearly shown in Figs. 2 to 5 of the drawings.

The reflector devices comprise a sleeve 3 75 that engages the rod 1, is laterally swingable and has vertical adjustment upon the said rod 1, it being held to its lateral and vertical adjustments by a set screw 4, as shown.

To the sleeve 3 is rigidly connected an outwardly projected U shaped frame 6, the inner ends of which are riveted, or otherwise fixedly secured to the sleeve 3, as at 60, and the outer ends of said frame are closed together and shaped to form a bearing 61 85 adapted to receive a socket 70 (see Fig. 6) of another bifurcated frame 7, hereinafter referred to, as the glare reflector supporting frame, the said reflector, generally designated 8, being fixedly held in the bifurcated 90 ends 71 of the said frame 70.

9 designates a clamp screw which engages the sleeve 70 and is adapted to hold it to any of its turned positions on the bearing 61, it being understood that the said connections 95 61, 9 and 70 provide for readily tilting the glare reflector 8 to any desired vertical angle, as shown in Fig. 4.

The glare reflector 8 is an oval shaped mirror glass that is provided at or near its 10 center with a clear space or eye portion 80. The glass 8 is held within a metal rim 10 that engages the edge of the glass and has clamp portions 11 that bend over the back of the glass and a pair of oppositely disposed members 12—12 that pass through and are clamped over the outer bifurcated ends of the forked supporting frame 7, (see Fig. 5).

From the foregoing taken in connection 11 with the drawing the complete construction, the manner of its use and the advantages

of my invention will be readily apparent to those familiar with the driving of motor vehicles.

The parts are so assembled that they may be readily applied to one of the side members of a wind shield supporting frame, inside of the shield, adjusted at the desired horizontal angle for deflecting the incoming light rays against the reflector, to one side of the roadway, and with the mirror glass inclined in vertical direction for reflecting the rays downwardly, as desired.

In practice, I find it best to set the device at an angle of 15° since at such angle the driver can see with his left eye through the clear or eye portion 80 of the glass and look forward with the other eye beyond the other side edge of the reflector, it being understood that the light engaging the mirror glass is deflected back into the ditch alongside of the road, and serves as an additional advance light for the car carrying my glare reflector.

What I claim is:

25 1. A glare reflector for automobiles comprising the following elements in combination; a bifurcated frame, a vertical supporting rod, operative connections that join the bifurcated frame to the rod for vertical and horizontal adjustment, the said bifurcated frame including portions bent toward each other and terminating in angled extensions clamped together to constitute a horizontal bearing, a second bifurcated frame, having the outer ends of the spread members joined to form a socket for engaging the aforesaid bearing, to provide for vertically swingable adjustments of said second frame, and a glare reflector supported between the separated ends of the said second frame and operative connections between the glare reflector and the said second frame to provide for sustaining the said glare reflector.

ing the aforesaid bearing, to provide for vertically swingable adjustments of said second frame, and a glare reflector supported between the separated ends of the said second frame and operative connections between the glare reflector and the said second frame to provide for sustaining the said glare reflector.

2. A glare reflector for automobiles comprising the following elements in combination; a bifurcated frame, a vertical supporting rod, operative connections that join the bifurcated frame to the rod for vertical and horizontal adjustment, the said bifurcated frame including portions bent toward each other and terminating in angled extensions clamped together to constitute a horizontal bearing, a second bifurcated frame, having the outer ends of the spread members joined to form a socket for engaging the aforesaid bearing, to provide for vertically swingable adjustments of said second frame, and a glare reflector supported between the separated ends of the said second frame and operative connections between the glare reflector and the said second frame to provide for sustaining the said glare reflector.

EDWARD C. LYTHE.
